UNITED STATES PATENT OFFICE.

HEINRICH KOPPER, OF MÜLHEIM-ON-THE-RUHR, GERMANY.

REGULATING AND REVERSING APPARATUS FOR REGENERATING GAS-FURNACES.

1,036,266.

Specification of Letters' Patent. Patented Aug. 20, 1912.

Application filed September 26, 1911. Serial No. 651,362.

To all whom it may concern:

Be it known that I, HEINRICH KOPPER, a subject of the German Emperor, residing at Mülheim-on-the-Ruhr, in the Rhine Province, Prussia, Empire of Germany, have invented certain new and useful Improvements in Regulating and Reversing Apparatus for Regenerating Gas-Furnaces, of which the following is a specification.

10 The present invention relates to regulating and reversing apparatus for regenerating gas furnaces whereby the flow of the gas to be burned and the burned gas through the apparatus is controlled by means of varying 15 water levels.

In my Patent No. 956,103 of April 26, 1910, which relates to a similar apparatus, I employ for the regulation of the water levels, receptacles in which the discharges 20 are adjusted by means of a rocking member. In the present invention, the movement of the rocking member is directly transmitted to the receptacles, that is to say, the receptacles are caused to swing up and down.

25 To make my invention more clear, the same is illustrated in the accompanying drawing, in which similar reference letters denote corresponding parts and in which— Figure 1 is a top plan view of the apparatus and a partial section on line A—B of Fig. 2 and Fig. 2 is a front elevation of the apparatus and a partial section on line C—D of Fig. 1.

In the drawing, which forms a part of 35 this specification, 1 denotes a vessel of prismatic or cylindrical shape, which by means of partition walls 2, 3, 4, 5, 6, 7, 8 and 9 is divided into a plurality of compartments or chambers I, II, III, IV, V, VI, VII and 40 VIII. The said walls extend radially, meeting in the center and are connected to a centrally extending vertical piece 10. As in the patent above referred to, these partition walls are made to extend either not 45 quite to the bottom or not quite to the top. The walls that extend not quite to the bottom are 2, 4, 6 and 8 and those extending not quite to the top are 3, 5, 7 and 9.

At the back of the vessel 1 a chimney flue 50 11 is provided, while at two opposite sides of the vessel, flues 12 and 13 are provided, through which the gas is allowed to circulate through the regenerating gas furnace (not shown). Fixed to the bottom 14 of the vessel are pipes 15 and 16, through which the water is conducted into the different

compartments. The pipe 16 terminates into the vessel underneath the partition wall 6 so that the water conducted therethrough is allowed to pass to the chambers or compartments IV and V. A branch 16^a of this pipe terminates into the vessel underneath the partition wall 2, so that the water flowing therethrough is allowed to enter the compartments I and VIII. In a similar manner, the pipe 15 terminates into the compartments VI and VII while its branch 15^a terminates into the compartments II and III.

The supply pipe 15 is connected by means 70 of a hose 17 to a receptacle 18 and the pipe 16 communicates by means of a hose 19 with a receptacle 20. The receptacles 18 and 20 are provided with overflow pipes 21 and 22 respectively and are connected by means of 75 links 23 and 24 respectively to a rocking member 25 fulcrumed at 26. Connected to the pipes 15 and 16 are supply pipes 27, 28 respectively, through which the water during the operation of the apparatus is supplied to the latter. The vessel, too, is provided with overflow pipes 29 and 30, which as the overflow pipes 21, 22 convey the water into discharges 31, 32 respectively. The gas to be burned is conveyed into the chambers 85 V and VI by means of a supply pipe 33.

In the position shown in Fig. 2, the receptacle 20 is situated at a higher level than the receptacle 18. The water supplied through the pipe 27 enters through the pipes 15 and 15^a the compartments VI and VII as well as II and III. Simultaneously, it also flows through the pipe 17 entering the receptacle 18, from which it passes through the overflow pipe 21 into the discharge 31. The 95 level of the water in the compartments II, III, VI and VII adjusts itself in accordance with the position of the overflow pipe 21. In a similar manner, the water flows through the supply pipe 28 into the 100 pipes 16 and 16^a and thence into the compartments I, IV, V and VIII as well as through the hose 19 into the receptacle 20. The level of the water in the compartments I, IV, V and VIII depends upon the position 105 of the overflow pipe 22. In accordance with the movement of the rocking member 25, the two receptacles 18 and 20 alternately adopt a higher and lower position and owing to this, the level of the water 110 in the different compartments changes, the level in the compartments II, III, VI and

VII being dependent upon the level of the receptacle 18 and the level of the water in the compartments I, IV, V and VIII being dependent upon that of the receptacle 20. In the position shown, the compartments II, III, VI and VII receive little or no water at all, so that the lower edges of the partition walls 4 and 8, which do not extend quite to the bottom, are sufficiently above the water level to permit of a passage of the gas underneath said walls. In the compartments I, IV, V and VIII, the water level reaches up to the opening leading into the overflow pipe 30, so that here the passage of the gas under the walls 2 and 6 which extend not quite to the bottom is rendered impossible. When the gas enters through the pipe 33 into the vessel, it first passes into the compartments V and VI. From the compartment V its passage to the compartment IV is prevented, as the wall 6 is submerged in the water contained in the compartments IV and V. On the other hand, from the compartment VI the gas is allowed to flow into the compartment VII under the wall 8, which does not reach the water level, and thence into the flue 13. Although the passage of the gas from the chamber VII into the chamber VIII over the wall 9 is possible, yet being unable to escape from the chamber VIII into the chamber I, owing to the high water level, the gas is forced to pass through the flue 13 into the regenerating gas furnace and returning through flue 12, it passes through chambers III and IV. From the latter, the passage of the gas to the chamber V for the above named reason being impossible it takes its way under the wall 4 into the chamber II and thence into the atmosphere through the chimney flue II. If it is desired to have the gas circulate through the regenerating furnace in reverse direction, all it is necessary to do is to accordingly adjust the rocking member 25. The water contained in the compartments I, IV, V and VIII up to the opening in the overflow pipe 30 is caused to flow through the pipes 16 and 16^a and hose 19 into the lowered receptacle 20, whence through the overflow pipe 22 it passes into the discharge 32. Thus, the above named compartments are partly or wholly emptied and the gas is allowed to freely pass under the walls 2 and 6 which do not extend quite to the bottom of the vessel. As by the adjustment of the rocking member 25, the receptacle 18 is raised, the water contained therein is caused to flow through the hose 17, and pipes 15 and 15^a into the chambers II, III, VI and VII, whence it is discharged through the overflow 29. The gas again entering through the pipe 33 into the chambers V and VI no more can pass under the wall 8, which is submerged in the water, into the chamber VII, and is forced to flow under the wall 6

into the chamber IV, thence into the flue 12 from which it circulates through the regenerating furnace in reverse direction, and in returning through flue 13, it enters the chamber VIII, passes thence under the wall 2, into the chamber I and finally escapes into the atmosphere through the chimney flue 11. If it is desired to completely stop the passage of the gas into the regenerating furnace, the rocking member 25 must be adjusted into horizontal position, whereby the receptacles 18 and 20 become so positioned that the corresponding chambers are filled with water up to the overflow pipes 29 and 30. In order to facilitate the adjustment of the lever 25, the same is counter-balanced by a weight 35.

In the present example, the flues 12 and 13 are arranged at the sides of the vessel, which is advantageous, because the gas alternately is forced to pass through the different compartments and to carry the soot through the chimney flue into the atmosphere.

In the present example, the walls of the compartments in the vessel are made solid, although as in my former Patent 956,106, they may be made hollow for the purpose of containing a cooling medium.

Having thus described the nature of my invention, I do not wish to restrict myself to the particular construction set forth and illustrated, as various modifications may be made by those skilled in the art without departing from the spirit of my invention.

What I claim and desire to secure by Letters Patent is:

1. In the herein described regulating and reversing apparatus, the combination with a vessel divided into a plurality of water-containing chambers communicating with one another partly at the top and partly at the bottom, of conduits supplying gas to and conducting it away from the said chambers, conduits for supplying water to the said chambers and vertically reciprocating receptacles having discharge openings and communicating with the said chambers and the said water supplying conduits.

2. In the herein described regulating and reversing apparatus, the combination with a vessel divided into a plurality of water-containing chambers communicating with one another partly at the top and partly at the bottom, of conduits supplying gas to and conducting it away from the said chambers, conduits for supplying water to the said chambers and vertically reciprocating receptacles having discharge openings and flexible water conduits connecting said receptacles with the said chambers and communicating with the said water supplying conduits.

3. In the herein described regulating and reversing apparatus, the combination with a vessel divided into a plurality of water

containing chambers communicating with one another partly at the top and partly at the bottom, of conduits supplying gas to and conducting it away from the said chambers, conduits for supplying water to the said chambers, receptacles having discharge openings and communicating with the said chambers and said water supplying conduits and a rocking member from which the said receptacles are suspended.

4. In the herein described regulating and reversing apparatus, the combination with a vessel divided into a plurality of water-containing chambers communicating with one another partly at the top and partly at the bottom, of conduits supplying gas to and conducting it away from the said chambers, conduits for supplying water to the said chambers, receptacles having discharge openings, flexible water conduits connecting said receptacles with the said chambers and with the said water supplying conduits and a rocking member from which the said receptacles are suspended.

5. In the herein described regulating and reversing apparatus, the combination with a vessel divided into a plurality of water-containing chambers communicating with one another partly at the top and partly at the bottom, of conduits supplying gas to and conducting it away from the said chambers, conduits for supplying water to the said chambers, receptacles communicating with the said chambers and the said water supplying conduits, and overflow pipes in the said receptacles and chambers.

6. In the herein described regulating and reversing apparatus, a polygonal vessel, a centrally vertical piece in said vessel and partition walls extending radially at a right angle from the outer walls to the said central piece of the said vessel and dividing the latter into a plurality of chambers, some of said partition walls extending not quite to the bottom and some not quite to the top of the vessel.

7. The herein described regulating and reversing apparatus, comprising a polygonal water-containing vessel having discharge openings, partition walls extending radially through the center thereof and dividing the said vessel into a plurality of

chambers, some of said walls extending not quite to the bottom and some not quite to the top of the vessel, conduits supplying gas to and conducting it away from said vessel, two vertically reciprocating receptacles having discharge openings, one of said receptacles communicating with some of said chambers and the other with the rest of said chambers and conduits supplying water to said vessel and said receptacles.

8. The herein described regulating and reversing apparatus, comprising a polygonal water-containing vessel having discharge openings, partition walls extending radially through the center thereof and dividing the said vessel into a plurality of chambers, some of said walls extending not quite to the bottom and some not quite to the top of the vessel, conduits supplying gas to and conducting it away from said vessel, two receptacles having discharge openings, a rocking member from which said receptacles are suspended, one of said receptacles communicating with some of said chambers and the other with the rest of said chambers and conduits supplying water to said vessel and said receptacles.

9. The herein described regulating and reversing apparatus, comprising a polygonal water-containing vessel having discharge openings, partition walls extending radially through the center thereof and dividing the said vessel into a plurality of chambers, some of said walls extending not quite to the bottom and some not quite to the top of the vessel, conduits supplying gas to and conducting it away from said vessel, two receptacles having discharge openings, a rocking member from which said receptacles are suspended, flexible conduits conductively connecting one of said receptacles with some of said chambers and the other with the rest of said chambers and conduits supplying water to said vessel and said receptacles.

In testimony whereof I affix my signature in presence of two witnesses.

HEINRICH KOPPER.
